A. ALDRICH

PAPER MAKING MACHINE

Filed Oct. 19, 1925

Patented May 11, 1926.

UNITED STATES PATENT OFFICE.

ALONZO ALDRICH, OF BELOIT, WISCONSIN.

PAPER-MAKING MACHINE.

Application filed October 19, 1925. Serial No. 63,282.

My invention relates to paper making machines, particularly of the Fourdrinier type.

One of the objects of the invention is to prevent the wire of a Fourdrinier machine from wearing grooves in the suction box covers, thereby wearing wire and preventing proper guiding.

Another object of the invention is to secure this result automatically by the operation of the machine, and furthermore, to secure it by means of the travel of the wire itself.

Another object of the invention is to secure the aforesaid results without the addition of any substantial number of moving parts, and without encumbering the machine with such parts, and without transmitting operating power from one part of the machine to another.

20 In the accompanying drawings Fig. 1 is a side elevation of a Fourdrinier end embodying my invention;

Fig. 2 is an end-elevation of a portion of the mechanism more directly involved in carrying out the invention;

Fig. 3 is a plan view of the same; and

Fig. 4 is a side elevation of the same.

Referring to the drawings, I show one type of Fourdrinier machine for the purpose of illustrating the invention, although it should be understood that the invention can be applied to various other types and forms of machine.

In the machine shown a table 1 is provided with a set of table rolls 2—2 and a breast roll 3, over all of which the wire 4 travels. Various other parts of the machine are also shown, but all of them will not be described as they are not all concerned in the invention.

40 In order to prevent the traveling wire 4 from forming grooves in the suction box covers, and in order to secure other advantages, arrangement is made for giving the wire 4 a slight lateral motion from side to side as it travels longitudinally of the machine. This secures the desired result, and not only prevents grooving of the suction box covers, but also prevents wearing the wire which would make guiding difficult. This lateral or side to side movement of the wire is desirably secured automatically by the operation of the machine itself, and preferably by means of a wire roll operated by the travel of the wire.

45 In the arrangement shown, which of

course is understood to be only one of various arrangements which could be used for the purpose, I arrange a wire roll 6 underneath table 1 and mount it so that one end, the nearest end in Fig. 1, may be moved slightly back and forth in a more or less horizontal manner, so that said roll will be inclined to the direction of movement of the wire, first in one direction and then in another direction. This inclination of the roll first to one side and then to the other side of a medium line running directly at right angles to the direction of travel of the wire, will cause the wire to move laterally, first in one direction and then in another, and so cause a slight weaving of the wire back and forth laterally which will continually vary its position on the suction boxes, the table and other rolls, and so accomplish the desirable results above set forth.

As one arrangement for securing this swinging or vibratory movement on the part of the roll 6, preferably by the travel of the wire itself, the swinging or moving end of said roll is mounted on a sliding bearing 7 (Figs. 2, 3 and 4), mounted to slide on a more or less horizontal guide or slideway 8, and this sliding bearing 7 is 80 pivotally connected at 9 with a bell crank 10, whose other arm 11 is pivotally connected at 12 with a link 13 connected with a crank pin 14 on a rotary member or wheel 15. The latter is carried by a rotary shaft 16 carrying a worm wheel 17 which meshes with a worm 18 carried by the shaft 19 of said wire roll 6. The slideway 8 may be mounted on a suitable frame 8^a, and the worm wheel shaft 16 may be mounted on a suitable stand 20, giving the various parts suitable support.

By this arrangement the rotation of the wire wheel 6 by the travel of the wire will cause the worm 18 to turn worm wheel 17 and this in turn will rotate shaft 16 and cause 100 crank pin 14 to vibrate bell crank 10 and so move slide 7 back and forth on slideway 8, thereby giving the wire roll 6 such a vibratory or swinging movement as will cause it to become inclined first in one direction and then in another to the line of travel of the wire, and so cause the wire to move laterally or from side to side first in one direction and then in another.

From the foregoing it will be seen that 110 the wire is laterally shifted to secure the desirable results set forth and that this is

accomplished in a simple and effective manner directly from the travel of the wire itself and without any additional moving parts of consequence, and without any transmission of power from other parts of the machine to the roll or device which accomplishes the wire shifting operation.

It will be understood that changes and modifications may be made without departing from the spirit of the invention.

What I claim is:

1. A Fourdrinier machine having a device operated by the wire and means whereby said device by its operation continually shifts the wire from side to side.
2. A Fourdrinier machine having a device rotated by the wire and means whereby said device by its rotation continually shifts the wire from side to side.
3. A Fourdrinier machine having a wire roll mounted to effect a lateral shifting of the wire and means operated by said roll for effecting such shifting movement so as to continually shift the wire from side to side.
4. A Fourdrinier machine having a wire roll mounted for swinging movement to cause the lateral shifting movement of the wire and means operated by the rotation of said roll for continually swinging the same so as to shift the wire continually from side to side.
5. A Fourdrinier machine having a wire roll mounted for swinging movement to effect the lateral shifting movement of the wire and means operated by said roll for continually effecting such swinging move-

ment so as to shift the wire continually from side to side.

6. A Fourdrinier machine having a wire roll mounted for swinging movement to effect the side to side shifting movement of the wire and means operated by the wire for continually effecting such swinging movement of said roll so as to continually shift the wire from side to side, said means comprising a worm and wheel arrangement operated by the roll and means for moving one end of the roll controlled by said worm and wheel arrangement.

7. A Fourdrinier machine having a wire roll mounted for lateral swinging movement to effect the lateral shifting movement of the wire, a sliding bearing for said roll, a worm carried by the roll spindle, a worm wheel cooperating with said worm, a rotary shaft carrying said worm wheel, a crank carried by said rotary shaft, and a bell crank link connected with said crank and also connected with said sliding bearing to effect the reciprocation of the latter.

8. A Fourdrinier machine having a wire roll mounted to permit swinging or vibratory movement to effect the lateral shifting of the wire, and means operated by the rotation of said roll for continually effecting such swinging or vibratory movement so as to continually shift the wire from side to side.

In witness whereof, I hereunto subscribe my name this thirtieth day of September, A. D., 1925.

ALONZO ALDRICH.
